UNITED STATES PATENT OFFICE.

EDWIN CRAWLEY, OF NEWPORT, KENTUCKY.

WASHING-MACHINE.

SPECIFICATION forming part of Letters Patent No. 243,856, dated July 5, 1881.

Application filed November 2, 1880. (Model.)

To all whom it may concern:

Be it known that I, EDWIN CRAWLEY, a resident of the city of Newport, in the county of Campbell and State of Kentucky, have invented certain new and useful Improvements in Washing-Machines, of which the following is a specification.

The object of my invention is to provide a new, effective, and economical means whereby, with the aid of a suitable liquid, raw material, as wool, &c., and fabrics made from wool, flax, or cotton, &c., as clothing, &c., may be quickly cleaned and purified.

My invention relates to that class of washing-machines which employ a revolving cylinder as a receptacle for the material to be washed; and the principal features of my invention consist of such a cylinder in combination with suitable mechanism whereby the material to be washed may be subjected, while in said cylinder, to a process consisting in alternately squeezing and tumbling it.

Ordinarily in the washing of fabrics they are subjected to a rubbing movement, which rapidly abrades them and wears them out. My invention dispenses altogether with the necessity of rubbing the material to be washed, and accomplishes the cleansing of it by the process of alternately squeezing and tumbling it.

Other features of my invention consist in the particular mechanism hereinafter described, which I have invented and selected to carry into effect the principal feature of my invention.

In the accompanying drawings, Figure 1 is a view, in perspective, of a washing-machine embodying my invention, a portion of the inclosing-tub and of the cylinder being broken away to show the interior construction thereof. Fig. 2 is a perspective view of an end of one of the staves, showing the construction thereof. Fig. 3 is a view, in perspective, of the end frame of the cylinder. Fig. 4 is a side elevation of the plunger or squeezer, which operates within the cylinder upon the material to be washed, the two layers or disks of wood constituting the center of said plunger being respectively broken away in part. Fig. 5 is an edge elevation of the plunger shown in Fig. 4. Fig. 6 is a central cross-section of the plunger, taken at the dotted line *x x*, Fig. 4.

Fig. 7 represents one end of the lid of the cylinder.

A indicates a tub or receptacle for holding the cylinder and the liquid to be used in the cleaning of the material to be washed. This tub is supported in any suitable way—as, for example, by legs *a*—and is also preferably provided with a suitable cover or lid, *b*.

B indicates the hollow cylinder, within which the goods to be washed are placed, supported at each end by a journal, *d*, and rotating in a bearing at its respective end of the tub A. The cylinder is constructed as follows: The supporting-frames consist of end pieces, C, Fig. 65 3, preferably cast in one piece, and consisting, in general, of disk or spider D, provided on its inner side with a horizontal flange, E, and with partition lugs F, to keep the staves apart and in their places. Rods G connect the two 70 end pieces, C, together. In the present instance the ends of each rod are diminished in size, so as to leave a shoulder which rests against the inner face of one of the pieces C, and that part of the end which is of diminished size projects 75 through and beyond the piece C, and that portion of said bolt which projects beyond the outer face of the said piece being provided with a screw-thread, a nut screwed thereon holds the spider securely to the bolt and against 80 the shoulder of the latter.

The staves H are constructed of such width that each of their ends shall closely fit one of the spaces between the partition-lugs F, and of such length as to fit closely between the inner faces of the spiders or disks D, and the staves are then secured in position by means of threaded bolts, each being screwed into one of the holes *f* of flange E, the holes *f* being screw-threaded. Each stave is provided with 90 one or more longitudinal grooves, I, located on the inner side of the stave. Each of these grooves receives one of the fingers or projections J on the periphery of the ring *g* of the plunger K. Each stave has a number of perforations, *n*, extending from outside to inside, whose size and number will depend upon the specific description of washing to which the machine is to be applied. This plunger K is constructed as follows: The ring *g* has a flange, 100 *h*, projecting inwardly from the center thereof, against which are placed the two wooden disks

L, bolted together in any suitable manner, and which disks so bolted are held in place by the flange h projecting between them. These wooden disks are perforated with holes m, extending from side to side. The size and number of these holes will depend upon the specific description of washing to which the machine is to be applied. The perforations n in the cylinder are for the easy circulation of the liquid to and from the material to be washed, and the perforations m in the plunger are conduits for the free egress of the liquid from the material being washed while pressed by the plunger.

15 The ring g is provided with the inwardly-projecting eyes, through which the rods G pass when the plunger is in position.

Arms M, of any suitable number, project from the periphery of ring g, and at their outer end carry a thread, N. This thread may be either a right or left hand thread, and may be single, double, treble, quadruple, &c., as is preferred, according to the specific purpose for which the machine is to be employed. It must be borne in mind that when a double thread is employed each of the threads need not be in length more than the half of a circle; if a treble thread be employed, each of the threads need not be in length more than the third of a circle; and for every increase of the number of threads there may be a proportionate decrease in the length of the thread. In the present instance the thread is double, and each thread is about the half of a circle, excepting that the ends of each of the threads lap the ends of the other, so that before one thread disengages from one of the female threads the other thread will engage the other female thread. The pitch of the thread is to be varied according to the speed at which it is desired that the plunger shall move and the degree of pressure with which the plunger shall press the material to be washed. All of the plunger K, excepting the threads N, is within the cylinder, the faces of the plunger being parallel to the faces of the ends of the cylinder. The arms M pass through the openings between the staves.

Where the end pieces, C, are spiders a disk of wood is placed against that side of each end piece which is toward the interior of the cylinder, in order to present a solid bulk-head to hold the material to be washed up against the pressure of the plunger, and also to prevent said material from falling out at the end 55 of the cylinder. This wooden disk fits closely up to the flange E.

Various modes of making the female screw-thread or its equivalent may be effectively employed. In the present instance I employ three 60 bars, P, running longitudinally with the tub, one of these bars being fastened at the front side of the tub, another at the rear side thereof, and a third at the bottom of the said tub. Each bar, on the side of it which is toward the 65 cylinder, carries a number of friction-rollers, R, each rotating loosely on a stationary pivot fixed to the bar P. The thread N fits between

two adjacent rollers. The size of the rollers depends upon the pitch of the threads N and the thickness of these threads, and the distance that the centers of adjacent rollers are apart will depend upon the pitch of the threads N. The number of rollers to be employed will depend upon the length of the machine, a sufficient number being employed to cause the 75 plunger to move from one end of the cylinder to the other.

Instead of rollers R, a series of lugs may be substituted for the wheels, a lug being used in place of each wheel, or a series of grooves in 80 the sides and bottom of the tub may be employed, instead of the wheels, the thread or threads fitting into these grooves. Conversely a line of rollers or series of studs following the line indicated by the thread or threads, as 85 the case may be, may be substituted for said thread or threads on the periphery of the plunger, the rollers or studs fitting into the grooves last mentioned in the sides and bottom of the tub. The cylinder B is to be rotated by any suitable power. In the present instance the cylinder is rotated by a crank, T, affixed to that end of journal d which projects beyond the outer side of the end of tub A.

Any suitable way of opening the cylinder, 95 for the introduction therein of the material to be washed, and for the removal of said material therefrom, and of then closing the cylinder, may be employed; but a convenient method of accomplishing these operations is as follows: The staves of the present cylinder, as will be observed, consist of pairs of broad staves and pairs of narrow staves, the broad and narrow pairs alternating around the cylinder. One pair of these broad staves are 100 held together at each end by two small arched pieces, S, (shown in Fig. 7,) which latter, when in place, lie everywhere closely against the periphery of the flange E, one of the lugs, F, being cut away so as to let the arched pieces 105 down upon said flange. One end of said pair of staves rests upon and is bolted to one of said pieces S, and the other end of said pair rests upon the other of said pieces S and is bolted thereto. This pair of staves is held 110 down at each end in place on the flanges E by an eye projecting from the outer side of the piece S, and which eye receives a hook swung from the outer face of piece C.

The mode in which my invention operates 115 is as follows, viz: A sufficient quantity of the liquid to be employed in washing the material to be cleansed is placed in the tub A. The plunger being at the middle of the cylinder, as shown in Fig. 1, the movable pair of staves 120 or lid is moved to one side, and one-half of the material to be washed is introduced into the cylinder on one side of the plunger, and the other half of said material on the other side of said plunger. The lid is now replaced 125 and fastened down. The crank T is turned in one direction, and the plunger, through the combined action of its thread or threads and the rollers R, is moved toward one end of the cylinder. 130

der, pressing up and squeezing the material to be washed between it and the said end of the cylinder. At the same time the cylinder is being revolved and tumbles the loose material present in the other portion of the cylinder, and thereby contributing to force the liquid through the material and thereby cleanse the same. The crank is now turned in a direction the reverse of which it was last turned, and the plunger is caused to approach toward and to squeeze that material which has just been tumbled, and which is on the opposite side of the plunger from that where the material which has just been squeezed lies, and the material first squeezed is, in its turn, tumbled. These operations of squeezing and tumbling are alternately repeated till the material is thoroughly cleansed, when the latter is removed and a new stock of dirty material introduced into the cylinder, to be cleansed in like manner.

The plunger, it will be observed, is held in vertical position and slides with the length of the cylinder, from end to end of the latter, on the rods G, which rods also cause the plunger to rotate with the cylinder. Each rod G passes through an eye, V, attached to the ring g of the plunger. The fingers J, shaped as shown, each fitting loosely in one of the grooves I, prevent any of the material in the cylinder from working in between the ring g and the inner surface of the staves as the plunger moves back and forth.

What I claim as new, and desire to secure by Letters Patent, is—

1. The combination, with the rotary cylinder located in tub A, the plunger and devices consisting of a spiral extension located outside of the said cylinder and connected to the plunger

by suitable devices, of projections on the interior of the tub, which conjointly operate to impart to said plunger a reciprocating movement within the cylinder, substantially as and for the purposes specified. 40

2. The plunger located within the rotary cylinder and provided with a screw-thread or threads, in combination with the tub having a counter thread or threads, substantially as and for the purposes specified. 45

3. In a washing-machine, the cylinder provided with longitudinal grooves and the plunger provided with fingers fitting into said grooves, in combination with a device consisting of a spiral extension connected to the plunger, and a tub provided with a counter thread or threads, whereby the rotation of the cylinder imparts to the plunger a reciprocating movement. 50 55

4. The rotary washing-cylinder provided with staves H, in combination with the plunger having arms M passing through openings between the staves, thread or threads N, located outside the cylinder, and tub provided with counter-threads, substantially as and for the purposes specified. 60

5. The rotary washing-cylinder provided with staves H, having longitudinal grooves I, in combination with a reciprocating plunger provided with fingers J, and arms M, and thread or threads N, and the rollers R, combined with the tub, substantially as and for the purposes set forth. 65 70

EDWIN CRAWLEY.
